UNITED STATES PATENT OFFICE.

FRED J. KELLY, OF LANSING, MICHIGAN.

WEEDER.

SPECIFICATION forming part of Letters Patent No. 727,804, dated May 12, 1903.

Application filed February 8, 1902. Serial No. 92,305. (No model.)

To all whom it may concern:

Be it known that I, FRED J. KELLY, a citizen of the United States, residing at Lansing, in the county of Ingham and State of Michigan, (whose post-office address is Lansing, Michigan,) have invented a new and useful Improvement in Weeders, of which the following is a specification.

My invention relates to that class of weeders in which the frame of the weeder is carried on wheels and the weeder-teeth are lowered into the ground or raised therefrom by a lever.

The objects of my improvement are to stiffen the bars carrying the teeth of the weeder, so as to prevent up-and-down vibration of the extremity of the bars without in any manner interfering with the freedom of movement or the adjustability of the weeder.

I attain these objects by the mechanism illustrated in the accompanying drawings, in which—

Figure 4 is a perspective view of the entire machine looking from the front right-hand side. Fig. 5 is a vertical section taken through the bars A and the upright sliding posts C, the dotted lines showing the frame in its raised position. Fig. 1 is a detail of the bars A; Fig. 3, a vertical section of the sliding posts C; and Fig. 2, the bearing B, in which it slides.

Similar letters refer to similar parts throughout the several views.

In the drawings, M represents the weeder-tooth bars, which are constructed in the usual manner and to which are attached the teeth P. These bars are connected to form the weeder-frame in the ordinary manner by braces N. I is the tongue of the machine, which is preferably formed of two parts joined together at one extremity and kept separated at the other extremity by a cross-bar G or other suitable device. Pivotaly attached to the tongue I at the point O is an auxiliary tongue H, also preferably formed of two parts. The tongue H is connected by the link Q to the weeder-tooth bars M and serves to support and steady them. A lever L is connected by a link E to the tooth-bars for the purpose of raising and lowering them. All these parts of the construction are well known and form no part of my present in-

vention, which consists in the peculiar construction which I shall now describe.

Pivotaly connected to one of the tooth-bars M by fastenings D are two upright posts C, Figs. 4 and 5, which slide through bearings or clips B, attached to the sides of the tongue I and braces A, extending from the upper extremity K of the posts C to the tooth-bars M, to which they are attached by bolts passing through elongated holes J in the foot of the braces, the holes being elongated for purposes of adjustment. The two braces A and the posts C thus form, in connection with the tooth-bars M, two half-trusses. These half-trusses only need to have the upper extremities K of the posts C connected together to complete the trusses and make a construction of extraordinary rigidity; but since in operation it is necessary to raise and lower the frame, and with it the posts C and braces A, it is not advisable to join the upper extremities of the posts by a rigid bar. The same effect, however, is produced by the cross-bar G, which rigidly retains the two parts of the tongue I at a fixed distance from each other. The upright posts C slide freely and yet closely through the clips B, and therefore in any different position in which they may be placed, whether raised, as shown by the dotted line in Fig. 5, or lowered, as in the entire lines, the truss structure is complete and the rigidity of the frame is secured, while still leaving an open space between the two upright posts above the tongue.

What I claim, and desire to secure by Letters Patent, is—

1. In combination with the tooth-bars of a weeder, upright posts attached at one end to said tooth-bars and diagonal braces connecting said tooth-bars with the other extremity of said posts, substantially as described.

2. In combination with the tooth-bars of a weeder, upright posts attached at one end to said tooth-bars, diagonal braces connecting said tooth-bars with the other extremity of said posts and clips adapted to receive said upright posts, substantially as described.

3. In combination with tooth-bars of a weeder, upright posts attached at one end to said tooth-bars, diagonal braces connecting said tooth-bars with the other extremity of said posts, clips adapted to receive said up-

right posts and means for keeping said clips at a uniform distance from each other, substantially as described.

4. In combination with the tooth-bars of a weeder, upright posts attached at one end to said tooth-bars, diagonal braces connecting said tooth-bars with the other extremity of said posts, a divided tongue and a cross-bar adapted to keep the parts of said tongue at a fixed distance from each other, substantially as described.

5. In combination with the tooth-bars of a weeder, upright posts attached at one end to said tooth-bars, diagonal braces connecting said tooth-bars with the other extremity of said posts, clips adapted to receive said up-

right posts, means for keeping said clips at a uniform distance from each other and means for raising and lowering said tooth-bars, substantially as described.

6. In combination with the tooth-bars of a weeder, upright posts connected therewith and diagonal braces connecting the extremities of said upright posts with said tooth-bars, said braces being furnished with an elongated opening at one extremity adapted to receive a bolt, substantially as described.

20 FRED J. KELLY.
